(No Model.)

J. GATES.

VESSEL AND APPARATUS FOR CUTTING CHANNELS IN WATER WAYS.

No. 308,153.

Patented Nov. 18, 1884.

UNITED STATES PATENT OFFICE.

JOHN GATES, OF PORTLAND, OREGON.

VESSEL AND APPARATUS FOR CUTTING CHANNELS IN WATER-WAYS.

SPECIFICATION forming part of Letters Patent No. 308,153, dated November 18, 1884.

Application filed April 30, 1884. (No model.)

To all whom it may concern:

Be it known that I, JOHN GATES, of Portland, in the county of Multnomah and State of Oregon, have invented a new and Improved 5 Vessel and Apparatus for Cutting Channels in Water-Ways, of which the following is a full, clear, and exact description.

This invention relates to a vessel and apparatus for cutting channels in water-ways in a simple, rapid, effective, and comparatively inexpensive manner.

The invention consists in the construction and arrangement of parts, as will be herein-after fully described and claimed.

Reference is to be had to the accompanying drawings, forming part of this specification, in which similar letters of reference indicate corresponding parts in all the figures.

Figure 1 is a plan view of a vessel and apparatus arranged for operation in accordance with my invention. Fig. 2 is a side elevation of the vessel in larger size, part being broken away to show the water-compartment; and Fig. 3 is a side elevation in still larger size 25 of a part of the bows of the vessel.

The letter A indicates the vessel, which has suitable tanks or compartments, A', to receive water-ballast for sinking the stern to any desired depth.

30 The vessel has apparatus, preferably steam-power boilers and engines, by which to propel her by a screw, B, fitted at the stern in the usual manner, in front of the rudder D, which latter may be shifted by connections from the forward wheel-house, E, and also from the aft steering-wheel, F.

At G is shown any approved hoisting apparatus, preferably a steam-windlass, on which to wind the lines or cables H I, leading from 40 the starboard and port sides, respectively, of the vessel, and a head line or cable, J. The outer ends of the cables H I J carry anchors K, or other devices, by which the vessel A may be anchored or held in position against moving forward or backward, and so that the head-line J may be paid out and the side lines, H I, hauled in when it is desired to back the vessel as the cutting of the channel by the back-wash from the screw B proceeds, as hereinafter described.

On a strong pin or shaft, L, held in eyes or

straps M, firmly bolted to the bows of the vessel A, are journaled two sheaves, N O. (Best shown in Fig. 3.) The starboard-line H passes from its outboard-anchor K (not shown) over the sheave N, and thence through the hawser-hole P on the port side of the vessel to the windlass G, and the port-line I passes from its outboard-anchor K over the sheave O, and thence to the windlass G, through a hawser-hole opposite the one P, and on the starboard side of the vessel. The lines H I are of about equal length—say, two thousand feet—and the head-line J may be of about the same length, and is also arranged to be hauled in by and paid out from the windlass G. By this arrangement of lines at and over the vessel's bows the vessel may be held from moving ahead and still be free to swing to either side at the stern on the sheaves N O or pin L as a center; or, in other words, the vessel hangs in the bights of the cables H I at the bows.

The operation is as follows: The vessel A, with the cables and attached anchors aboard, is steamed to the bar or shoal to be channeled, or to the channel to be deepened, and the line of the channel is first marked off or indicated by a center range of buoys or beacons, and two side ranges, which indicate the width or proposed width of the channel. The vessel is headed up-stream, or against the current, with the stern close onto the bar or shoal, and the anchors K of the lines H I J are set forward and aft of the vessel, the anchors of lines H I being lowered to hold the lines sufficiently spread apart backward from the vessel's bows to permit the vessel's stern to swing to either side range for the full width of the channel, and the head-line anchor set on the line of the center of the channel, as will be understood from Fig. 1, wherein the dotted lines indicate the side swing of the vessel. The vessel being now controlled by a helmsman at F and a leadsmen at R, will be backed carefully as the side lines, H I, are hauled in by the windlass G, and the head-line J paid out therefrom until the stern, now sunk by water-ballast to a given depth, touches the bar. The lines will now be made fast at the windlass and the screw B turned ahead, and as the vessel does not move ahead, because it is held by the aft anchors, the water will be

- forced backward by the screw B against the shoal or bar with sufficient force (assisted or not by the natural currents of the water-way) to dislodge the bottom deposits and cut a channel, and as the vessel steers quite the same as when "running off free," the stern will swing to either side and the keel will gage the clear depth of the channel across its full width to both side ranges, as will readily be understood. When the first clear cut is taken, the vessel will again be aligned with the center range and backed as before until she again touches bottom, when the cables will be made fast and the screw again turned ahead full speed for a second cut by the forcible water-currents from the screw to the full width of the channel, and like operations may be repeated for cutting or sluicing a channel of any desired length.
- 20 The cables H I J being flexible, are well adapted for use with anchors for holding the vessel when sluicing channels in water-ways having considerable swell or rise and fall of the water, which carries the vessel up and down when at work. Any tendency of the vessel's bows to work off of or away from the center range of the channel may be corrected by hauling in on either starboard or port cables H I, as required.
- 25 30 It will be understood that the use of the

pivot and sheaves L N O is not absolutely essential, as the vessel A may swing sidewise at the stern upon cables passing over fixed blocks at the bows, and the cables may be led to and worked by one or more windlasses G, in a 35 manner other than that above described; but the use of the sheaves is preferred, as they relieve friction and wear of the vessel and cables, and greatly facilitate the handling of the vessel during the progress of the work; 40 and the arrangement of the windlass is simple, effective, and labor-saving, and will admit of a steady backward feed, if desirable.

The above-described arrangement of the cables and windlass or capstan may be used with 45 a vessel fitted with a stern paddle-wheel for dislodging the bottom deposits in cutting or sluicing shallow channels, as will readily be understood.

Having thus described my invention, I claim 50 as new and desire to secure by Letters Patent—

The combination, with the bow of a vessel of the character described, of the cables H I J, windlass G, pulleys N O, brackets M, and pin L, substantially as set forth.

JOHN GATES.
